UNITED STATES PATENT OFFICE.

JOHN H. THIELER, OF LENORA, KANSAS

CRUDE-OIL BURNER.

No. 902,629.

Specification of Letters Patent.

Patented Nov. 2, 1908.

Application filed October 14, 1907. Serial No. 397,395.

To all whom it may concern:

Be it known that I, JOHN H. THIELER, a citizen of the United States, residing at Lenora, in the county of Norton and State 5 of Kansas, have invented certain new and useful Improvements in Crude-Oil Burners; and I do declare the following to be a full, clear, and exact description of the invention, such as will enable others skilled in the art 10 to which it appertains to make and use the same.

This invention relates to improvements in crude oil burners.

The object of the invention is to provide 15 a device of this character adapted to be applied to a stove in such a manner that the oil will be thoroughly vaporized, heated and mixed with air while being injected into the burner arranged within the stove.

20 A further object is to provide a crude oil burner having means to provide a top or down draft, thereby causing all the gases conducted in the vaporized oil to be burned; the construction also providing for the burning 25 of all soot.

With these objects in view, the invention consists of certain novel features of construction, combination and arrangement of parts 30 as will be more fully described and particularly pointed out in the appended claims.

In the accompanying drawings, Figure 1 is a vertical, sectional view of a heating stove showing the application of the invention thereto; Fig. 2 is a detail, perspective 35 view of the burner and its attachment removed from the stove; Fig. 3 is a detail sectional view through the lower end of the oil feeding or discharge pipe, showing the arrangement of the injecting nipple therein; 40 and Fig. 4 is a vertical sectional view through a portion of a cook stove, showing the application of the invention thereto.

Referring more particularly to Figs. 1 and 2 of the drawings, 1 denotes the burner, 45 which is in the form of a cast iron bowl 3 having a removable top, 2. The bowl 3 is provided with a laterally projecting flange, by means of which the same is tightly fitted to the lower portion of the stove. The top, 50 2, is provided with a series of openings or apertures, 4, through which the vaporized oil is ignited and adapted to burn. The top, 2, is preferably formed in two sections, one of which may be readily removed for any 55 desired purpose.

In the top 2 is formed a centrally disposed

aperture 5 into which is adapted to be inserted the lower end of an air conducting tube, or pipe, 6, said tube preferably tapering from its lower toward its upper end, 50 so where it projects through the top of the stove, and to which it is suitably secured.

Arranged above the upper end of the air conducting tube 6 is an oil discharge pipe 7 in the end of which is arranged an injector 55 tip, 8. The discharge end of the oil pipe 7 is preferably secured in place by a suitable fastening bracket 9. The oil conducting and discharge pipe is connected to an oil tank or other source of oil supply and is provided 70 with a controlling valve, 10, by means of which the flow of oil from said tank to the stove is controlled.

In Fig. 4 of the drawing, the device is shown applied to a cook stove, and when 75 constructed for this purpose is provided with a burner bowl, 12, formed in a suitable shape to fit within the fire box of the stove. The construction of the bowl 12 with the exception of the shape, is the same as that described in connection with the heating stove. Adapted to be connected with the bowl 12 is an air conducting tube 13 which projects through the front of the stove and extends 80 upwardly from the bowl at an angle as 85 shown.

When the device is constructed for use with a cook stove and provided with an inclined air conducting tube, it has been found necessary to provide an oil conducting tube 90 14, which is arranged within the air conducting tube and is provided at its outer end with a flared or funnel shaped mouth 15, which is arranged immediately below the injector tip in the end of the oil supply pipe. 95 The lower or inner end of the oil conducting tube 14 extends into the burner bowl, where the vaporized oil is discharged therefrom.

In using the device, the air conducting tube is primarily heated from a small wood fire kindled upon the burner bowl, which is adapted to rest upon the grate of the stove, whereby the oil injected into the upper end of said tube will be thoroughly heated and vaporized in passing through the tube 100 105 so that when the vaporized oil reaches the burner, the same will have been thoroughly mixed with the air, which is also heated in the conducting tube 6, and will be in condition to be ignited and burned through the 110 opening in the burner bowl. The burner tube will then be kept in a heated condition

by the flame from the burner. The oil conducting tube 14 is provided in connection with the air tube for the cooking stove arrangement to prevent the vaporized oil from being ignited in said air tube before reaching the burner bowl, said oil being vaporized in the conducting tube or pipe 14 by the heated air in the air conducting tube.

By providing the air conducting tubes 10 leading downwardly from the upper portion of the stove to the burner bowl, a top or down draft only is provided for the burner, which will cause all the gas in the oil to be burned, thus preventing the wasting of such gas by the passage of the same to the chimney, which would occur should a bottom draft be permitted to act on the burner. By the arrangement of the air conducting tube, as shown and described herein, it has also been found that all soot will be consumed.

From the foregoing description, taken in connection with the accompanying drawing, the construction and operation of the invention may be readily understood without requiring a more extended explanation.

Having thus fully described my invention, what I claim as new and desire to secure by Letters Patent, is:

30 1. A crude oil burner comprising a burner bowl adapted to be arranged within a stove to cover and close the grate therein, a flange on said bowl to engage the sides of the stove and thereby prevent an up-draft through the

latter, a sectional perforated top on said bowl, one section of which is removable, an air-conducting tube connected with said top, and an oil injecting pipe connected to the upper end of said tube, substantially as described.

2. A crude oil burner comprising a burner bowl having a perforated top formed in sections, one of which is removable, a tapering air-conducting tube connected at its lower larger end with said burner bowl and extending upwardly through the top of the stove, an oil supply pipe, and an injecting tip arranged in the end of said supply pipe, substantially as described.

3. A crude oil burner comprising a burner bowl, a perforated top, formed in sections, one of which is removable, an air conducting tube, an oil conducting and vaporizing tube arranged in said air conducting tube and projecting at its lower end into said burner bowl, a valved oil supply pipe, and an injector tip arranged in the discharge end of said pipe, whereby the oil therefrom is injected into said oil conducting and vaporizing tube, substantially as described.

In testimony whereof I have hereunto set my hand in presence of two subscribing witnesses.

JOHN H. THIELER.
